CLAIM

The ornamental design for an undercabinet light, as shown and described.

DESCRIPTION

FIG. 1 is a perspective view showing the bottom and front of an undercabinet light showing my new design;

FIG. 2 is a front elevational view thereof;

FIG. 3 is a rear elevational view thereof;

FIG. 4 is a left side elevational view thereof; the right side elevational view is a mirror image of the left side;

FIG. 5 is a top plan view thereof; and,

FIG. 6 is a bottom plan view thereof.

The broken lines shown on the drawings are for illustrative purpose only and form no part of the claimed design.
